UNITED STATES PATENT OFFICE.

JAMES WALTER GOLDEN, OF SWEETBRIAR, NORTH DAKOTA.

AUTOMOBILE ATTACHMENT.

1,076,974.

Specification of Letters Patent.

Patented Oct. 28, 1913.

Application filed December 18, 1912. Serial No. 737,453.

To all whom it may concern:

Be it known that I, JAMES W. GOLDEN, a citizen of the United States, and a resident of Sweetbriar, in the county of Morton 5 and State of North Dakota, have made certain new and useful Improvements in Automobile Attachments, of which the following is a specification.

My present invention is an attachment for 10 automobiles and relates particularly to an improved apparatus whereby to facilitate the cleaning and polishing of the brass parts of an automobile, the object of my invention being to provide a flexible power transmitting member having means at one end whereby it may be attached to a selected one 15 of the engine rotated shafts and having at its opposite end a rotary brush which may be either abrasive or polishing.

With the above in mind my invention resides in the features of construction, arrangement and operation to be now described with respect to the accompanying drawing, forming a part of this specification, and in which—

Figure 1 is a front elevation illustrating the practicable application of my invention. Fig. 2 is a detail longitudinal section through the brush carrying end of the flexible shaft. Fig. 3 is a vertical section taken centrally through the gear casing and a portion of the fan shaft of the automobile, and Fig. 4 is a horizontal section taken centrally through the gear casing and illustrating the connections between the casing and the machine.

Referring now to these figures, A indicates a substantially oval casing which is open at one side and provided with extensions *a* at its ends, which extensions are apertured for the reception of set screws *a'*. Across the open side of the casing extends a bearing strip A' and between this bearing strip and the front wall of the casing are disposed the intermeshing gears B and B'. These gears are provided with integral shafts *b*, *b'* respectively which have bearings in the strip A' and the front wall of the casing A and the shaft *b* which is extended beyond the open side of the casing and provided with a squared longitudinal bore extending therein on its inner end. The shaft *b'* of the gear B' is extended outwardly through the front wall of the casing A and a socket *c* is secured to the shaft by means of a transverse key or other equiva-

lent fastening member, the said socket being in turn secured upon one end of a flexible shaft C. At its opposite end, the flexible shaft C is provided with a holder upon 60 which a rotary brush E may be removably fastened.

In order that my invention may be quickly and conveniently connected upon an automobile, I provide the machine, such as indicated at D in Figs. 1, 3 and 4, with a forwardly extended fan shaft D' having a reduced squared extremity *d* and I preferably secure nuts or other internally threaded members *d'* within the interstices of the 70 radiator upon opposite sides of the fan shaft in order to conveniently receive the set screws *a'* at a time when the extended gear shaft *b* projects through the radiator and engages the reduced squared end of the fan 75 shaft.

It will thus be seen that my invention may be readily and quickly connected in operative position and that when so connected, the engine driven fan shaft will cause rotation 80 of the flexible shaft C through the gear wheels B and B', causing rotation of the brush E whereby the brass parts or trimmings of the automobile may be quickly cleansed or polished without the usual exertion incident to hand rubbing by the person 85 cleaning the machine.

It is to be apparent that after the parts have been cleaned my invention may be as readily and quickly detached and may be 90 stored away upon the machine and it is to be understood that the brush E may be any form of polishing wheel desired, that is, it may be a brush, a felt or like wheel adapted to receive a plastic abrasive composition or the like or it may be a finishing 95 wheel.

I claim;

1. An automobile attachment comprising a gear casing, means for attaching same 100 to an automobile front, and gears carried by the said casing and having shafts extended outwardly relatively in opposite directions, the extended shaft of one of the gears being provided with a squared longitudinal bore for application upon the similarly shaped extremity of an automobile fan shaft.

2. An automobile attachment comprising the combination with an automobile having 110 an extended fan shaft, and internally threaded members upon opposite sides of

the fan shaft of a gear casing having apertured side extensions and connecting members operating through said side extensions and adapted for engagement with the said 5 internally threaded members whereby to secure the gear casing in operative position, and gears mounted within the casing and one of which is provided with an extended

shaft having a squared longitudinal bore for engagement with the similarly shaped 10 extremity of the extended fan shaft.

JAMES WALTER GOLDEN.
